UNITED STATES PATENT OFFICE.

HENRY O. MAGNUSON, OF CHICAGO, ILLINOIS.

MOLDING-MACHINE.

1,352,295.

Specification of Letters Patent. Patented Sept. 7, 1920.

Application filed May 27, 1918. Serial No. 236,732.

To all whom it may concern:

Be it known that I, HENRY O. MAGNUSON, a citizen of the United States, residing at Chicago, in the county of Cook, State of Illinois, have invented certain new and useful Improvements in Molding-Machines, of which the following is a specification.

This invention relates to improvements in molding machines of that general type wherein a molding flask or a core-box is first clamped and then inverted to effect the separation of the pattern plate and pattern from the mold or to withdraw the core-box from the core. Many machines of this general type now in use and commonly known as rock-over machines, are quite cumbersome in structure, occupying considerable floor space and laborious to operate, involving the use of a clamp to secure the flask or core-box in position to be inverted, and necessitating the manual raising and rocking of the flask or core-box with the hinged support carrying the same over onto a receiving table or platform on which the box is deposited bottom side up; the separation of pattern or of the core-box being then effected by hand.

The principal object of the present invention is to provide a machine of simple and compact construction which shall be easier to manipulate, which may be operated by a single attendant from one side of the machine, and in which the inverting operation may be performed with a minimum of labor, and wherein the separation of the pattern from the mold or of the core-box from the core may be effected by power means. These and other desirable objects are secured by the machine of the present invention, which is characterized mainly by the provision of an invertible mold-clamping frame made in two hinged sections so as to be openable and journaled to swing on a suitable supporting frame and carrying a power-actuated table to support the flask or core-box, a cable when raised carrying the flask or core-box up into clamped relation to the upper transverse member of the invertible frame, so that the flask or core-box is securely held while the frame is inverted.

This invertible mold-clamping frame is so constructed that, when the mold or core-box is in the raised and clamped position, the center of gravity is above the pivot axis of the frame so that it will invert itself upon a slight push; while when the frame has

been inverted and the flask removed, the center of gravity of the empty frame structure in its inverted position is still above the pivot axis so that it may be automatically restored to normal or upright position by a slight push.

Other features of the invention reside in means for counter-balancing the hinged member of the frame so that it may be easily swung into and out of working position; and means for automatically locking the hinged frame member in working position.

The nature of the invention, its structural features, mode of operation, and advantages will be readily understood and appreciated by those skilled in the art from the following detailed description, taken in connection with the accompanying drawings wherein I have illustrated a practical and preferred embodiment of the invention, and in which—

Figure 1 is a front elevation of the machine;

Fig. 2 is a vertical section on the line 2—2 of Fig. 1, with the core-box shown in Fig. 1 omitted;

Fig. 3 is an elevation similar to that shown in Fig. 1, but showing the pivoted frame in clamping and inverted position;

Fig. 4 is a fragmentary end elevation as seen on the line 4—4 of Fig. 1 with the supporting frame omitted; and

Fig. 5 is a fragmentary detail illustrating the automatic locking device of the upper hinged frame member.

Referring to the drawings, 10 designates each of a pair of upright end members of the supporting frame of the machine that are suitably connected and braced by cross-bars 11. On the upper end of each frame member 10 is a journal bearing 12 in which bearings are supported the trunnions of a generally rectangular mold clamping and inverting frame which, in the preferred form here shown, comprises a lower U-shaped member 14 having the trunnions 13, and an upper inverted U-shaped member 15 that is pivoted at one end by a pivot shaft 16, to one end of the lower member 14. The lower frame member 14 is formed centrally thereof with a vertical sleeve 17, in which is mounted a pneumatic cylinder 18. Within the cylinder is a piston 19 connected by a piston-rod 20 to a table or platform 21, said table or platform in its lowered position resting upon the upper cylinder head 22 which, in turn, is secured to the upper

face of the lower frame member 14. On either side of the sleeve 17 are smaller sleeves 23 that form guideways for a pair of depending guide-rods 24 that are rigidly secured to the underside of the table 21, and insure the accurate vertical movements of the latter. The table 21 is designed to support the mold box, which may be a core-box such as that shown at 25 for the molding of core pieces, or may be the usual molding flask. In the former case the core-box is screwed or clamped to the table, and in the latter case the pattern plate is secured to the table. The motor cylinder is designed to be operated by fluid pressure, preferably compressed air, which enters through a line pipe 26 having a manually operable controlling valve 27 therein, from which valve are led flexible tubes 28 and 29 through one of the trunnions 13, the former leading into the lower end of the cylinder through a jarring valve 30, and the latter leading into the upper end of the cylinder.

The jarring valve 30 is mounted on the motor cylinder 18, and the plunger thereof is reciprocated through a lever 31 from a rod 32 secured to and depending from the table 21, the lower end of said rod having a foot 33 engaging with a forked arm of the lever 31. By means of a handle 34 on the rod 32 the latter may be turned on its longitudinal axis so as to disengage the foot 33 from lever 31 and thereby interrupt the operation of the jarring valve when the jarring of the mold has been completed.

The upper member 15 of the mold-clamping and inverting frame is provided at its free end with a self-locking latch best shown in Fig. 4 and comprising a shaft 35 journaled in and transversely of the frame member 15 and carrying on its opposite ends a pair of depending latch hooks 36, the lower hooked ends 36' of which engage beneath shoulders 37 formed on the lower frame member 14. The upper end of the right hand arm of the frame member 14, on which the shoulders 37 are formed, is beveled, as shown at 37' in Fig. 5, and the hook members 36' are correspondingly beveled on their rear sides so as to automatically slide over the shoulders 37 and engage beneath the latter under the influence of a coil spring 38 applied to the shaft 35. On one of the depending hook members 36 is a handle 39 by which the latch may be manually released when the upper frame member 15 is to be swung rearwardly for loading the table.

To partially counter-balance the weight of the upper frame member 15 and render the swinging movements thereof easy to perform, a counter-balancing spring 40 is applied to the pivot shaft 16, the closing movement of the frame member 15 acting to tension this spring, and the energy of the spring being given out as the frame mem-

ber is raised and swung back, acting in opposition to the weight of the latter. By employing a sufficiently powerful spring, the weight of the frame member 15 may be practically neutralized so as to render the operation of the latter very easy.

The machine is also equipped with means for automatically locking the mold-clamping and inverting frame in either of its two positions shown in Figs. 1 and 3 respectively. This consists of a segment plate 41 integral with or secured to the left-hand arm of the lower frame member 14 adjacent to the trunnion of the latter, said plate having a pair of notches 42 disposed 180° apart with reference to the axis of the trunnion, and a latch member 43 pivoted on the adjacent frame member 10 and having a locking nose 44 that is normally pressed into engagement with the periphery of the segment plate 41 by a spring 45 (Fig. 1) on the pivot shaft of the latch 43.

Secured to the underside of the transverse member of the upper frame member 15 are a pair of parallel horizontally extending rods or bars 46 that directly engage the top of the core-box or mold when the latter is raised and support the same when the frame is inverted to the position shown in Fig. 3.

In the operation of the machine, the core-box having been fastened to the table, the upper frame member or yoke 15 is swung rearwardly on its hinge 16, and the core-box is filled with sand. The air is then turned on to the motor and the box is jolted or jarred by the motor, controlled by the jarring valve 30. As soon as the box has been sufficiently jarred, the core-plate is placed on the core-box, and the member 15 is swung back to working position as shown in Fig. 1, being automatically locked in such position by the latch members 36 as soon as it is returned. The controlling rod 32 is then turned by the handle 34 to cut out the jarring valve, and the air entering beneath the piston 19 raises the table 21 and the box 25 until the latter is clamped between the table and the rod or bars 46.

In this position of the parts the loaded mold carrying frame is approximately balanced with reference to its axis, the center of gravity being slightly above the line of the axis. The latch 43 is then retracted and the upper member of the frame is given a slight push which suffices to overcome the equilibrium, and the frame swings over to the inverted position shown in Fig. 3, being automatically locked by the latch 43 in such position. The air is then reversed in the motor, which causes the table 21 and the box 25 to be raised, leaving the core-plate and core resting on the bars 46, whence they may readily be removed by hand. When the latter have been withdrawn, it leaves the

center of gravity of the empty frame again slightly above the pivot axis, so that by giving the frame member 14 a slight push, the frame swings back to upright position, 5 the latch 43 having been retracted to permit such movement.

It is believed that the structural features, mode or principle of operation, and the advantages of the present machine will be 10 clearly apparent to those skilled in this art without further detailed description. It is manifest that in this machine the operations of jarring, clamping and inverting the mold or core-box are performed with a minimum 15 of manual labor, lifting operations being practically eliminated. The machine is also characterized by extreme compactness, requiring much less space for its setting up and operation than rock-over machines at 20 present in use. The machine can be operated wholly from one side, thus saving time of the operator heretofore spent in walking from one side of the machine to the other.

It will be manifest that the apparatus as 25 shown and described may be modified in respect to details of structure and organization without altering the substantial character of the invention or sacrificing any of the advantages inhering therein; hence I reserve 30 all such variations and modifications as fairly fall within the spirit and purview of the appended claims.

I claim:

1. In a molding machine, the combination 35 of a supporting frame, a mold-clamping and inverting frame having trunnions on its opposite sides journaled in said supporting frame, said mold-clamping and inverting frame comprising upper and lower 40 frame members hinged together at one end on a horizontal axis lying transverse to the axis of said trunnions and separably connected to each other at their other ends, a table supported on said lower frame member and itself adapted to support a mold-box, and means for elevating said table within said mold-clamping and inverting frame whereby to clamp the mold-box 45 against said upper frame member.

50 2. In a molding machine, the combination of a supporting frame, a substantially rectangular mold-clamping and inverting frame comprising a generally U-shaped lower member having horizontal trunnions 55 journaled in said supporting frame and an inverted U-shaped upper member hinged at one end to one end of said lower member and separably connected at its other end to the other end of said lower member, a table supported on said lower frame member and itself adapted to support a mold-box, and means for elevating said table within said mold-clamping and inverting frame whereby to clamp the mold-box 60 against said upper frame member.

3. In a molding machine, the combination of a supporting frame, a mold-clamping and inverting frame having trunnions on its opposite sides journaled in said supporting frame, said mold-clamping and inverting frame comprising upper and lower frame members hinged together at one end on a horizontal axis lying transverse to the axis of said trunnions and separably connected together at their other ends, a cylinder 70 mounted in said lower frame member, a piston and piston-rod in said cylinder, a table on the upper end of said piston-rod adapted to support a mold-box, guides in said lower frame member on either side of said cylinder, and guide-rods rigid with said table and slidably engaged with said guides.

4. In a molding machine, the combination of a supporting frame, a substantially rectangular mold-clamping and inverting frame comprising a generally U-shaped lower member having horizontal trunnions journaled in said supporting frame and an inverted U-shaped upper member hinged at 85 one end to one end of said lower member and separably connected at its other end to the other end of said lower member, a cylinder carried by said lower frame member, a piston and piston-rod in said cylinder, a table on the upper end of said piston-rod adapted 90 to support a mold-box, and means for applying motive fluid to said cylinder whereby 95 the mold-box may be raised and clamped against said upper frame member.

5. In a molding machine, the combination 100 of a supporting frame, a mold-clamping and inverting frame journaled at its opposite sides in said supporting frame, a table, and a table-elevating motor mounted on the lower transverse member of said mold-clamping and inverting frame, said parts being in such approximate equilibrium that when a mold box on said table is raised into clamped engagement with the upper transverse member of said mold-clamping frame 105 110 the center of gravity of the loaded frame is the center of gravity of the inverted frame remains above the pivotal axis.

6. In a molding machine, the combination of a supporting frame, and a mold-clamping and inverting frame comprising a lower frame member having lateral trunnions journaled in said supporting frame 120 and an upper frame member hinged at one end to an end of said lower frame member, and means for counter-balancing the weight of said upper frame member during its swinging movements.

7. In a molding machine, the combination of a supporting frame, and a mold-clamping and inverting frame comprising a lower U-shaped frame member having lateral trunnions journaled in said supporting 125 130

frame, and an upper inverted U-shaped frame member hinged at one end to one end of said lower frame member, and a spring connected to the hinge-pivot of said upper frame member and assisting the opening and opposing the closing swinging movement of the latter.

8. In a molding machine, the combination of a supporting frame, and a mold-clamping and inverting frame comprising a

lower frame member having lateral trunnions journaled in said supporting frame, and an upper inverted frame member hinged at one end to one end of said lower frame member and at its other end provided with a spring latch for automatically locking it to the other end of said lower frame member when said last named frame ends are brought into meeting relation.

HENRY O. MAGNUSON.
